UNITED STATES PATENT OFFICE.

JAMES M. KEEP, OF NEW YORK, N. Y., ASSIGNOR TO THE TOWER MANUFACTURING AND NOVELTY COMPANY, OF SAME PLACE.

DESIGN FOR A PEN-RACK STAND.

SPECIFICATION forming part of Design No. 23,677, dated October 2, 1894.

Application filed May 15, 1894. Serial No. 511,366. Term of patent 7 years.

To all whom it may concern:

Be it known that I, JAMES M. KEEP, a citizen of the United States, and a resident of New York, county and State of New York, have invented and produced a new and original Design for a Pen-Rack Stand, of which the following is a specification, reference being had to the accompanying drawings, of which—

Figure 1, is a perspective view of the stand complete. Fig. 2, is a face view of one end of the stand. Fig. 3, is an edge view of one end of the stand.

My pen rack stand is composed of the two ends M. M., joined together by the bars N. N., the design for each end being a scalloped circular rim "A," inclosing a plain star shaped figure "B," the points "C" radiating to and being attached to the inner circle of the rim "A." The center of the star is open or depressed. This depression is surrounded by a

ring or bead "D" outlined by a groove "E." It is further composed of the rim inclosing the star being attached to and supported by legs L. L. which terminate downward with ²⁵ up-turned pedestals P. About midway between the legs is a cross-bar H, the upper edge of which is curved downward. The lower edge is curved upward, thus representing a brace or tie between the legs. ³⁰

The stand is necessarily made with opposite ends, each of which is of the same design. When these ends are united by bars as shown in Fig. 1, the pen rack stand is complete. ³⁵

I claim—

The design for a pen rack stand herein shown and described.

JAMES M. KEEP.
